UNITED STATES PATENT OFFICE

160,922

CUT HAIR BLOWER OR SIMILAR ARTICLE

Salvatore L. Ciulla, Port Richmond, N. Y.

Application April 10, 1950, Serial No. 9,097

Term of patent 14 years

(Cl. D86—10)

To all whom it may concern:

Be it known that I, Salvatore L. Ciulla, a citizen of the United States, residing at Port Richmond, Staten Island, in the county of Richmond and State of New York, have invented a new, original, and ornamental Design for a Cut Hair Blower or Similar Article, of which the following is a specification, reference being had to the accompanying drawing, forming part thereof.

Figure 1 is a side elevational view of a cut hair blower or similar article showing my new design;

I claim:

The ornamental design for a cut hair blower or similar article, as shown.

SALVATORE L. CIULLA.
